CLAIM

The ornamental design for a toilet, as shown and described.

DESCRIPTION

FIG. 1 is a perspective view of a toilet showing the new design.

FIG. 2 is a front view of the toilet of FIG. 1.

FIG. 3 is a rear view of the toilet of FIG. 1.

FIG. 4 is a side view of the toilet of FIG. 1.

FIG. 5 is an opposite side view the toilet of FIG. 1.

FIG. 6 is a top view the toilet of FIG. 1; and,

FIG. 7 is a bottom view the toilet of FIG. 1.

Broken lines show environment structure that forms no part of the claimed design.
